TEMPERATURE REGULATOR

William Major Polk, Santa Monica, Calif., assignor to
Eugene T. McKinnon, Pacific Palisades, and Alvin S.
Drutz, Los Angeles, Calif.

Filed Aug. 18, 1972, Ser. No. 281,977

Term of patent 14 years

Int. Cl. D10—04

U.S. Cl. D52—7 R

Fig. 1.

Fig. 2.

Fig. 3.

Fig. 4.

Fig. 5.

FIG. 1 is a side elevational view of the temperature regulator showing my new design;

FIG. 2 is a view taken along the line 2—2 of FIG. 1;

FIG. 3 is a view taken along the line 3—3 of FIG. 1;

FIG. 4 is a view taken along the line 4—4 of FIG. 2; and

FIG. 5 is a view taken along the line 5—5 of FIG. 2.

I claim:

The ornamental design design for a temperature regulator, as shown.
